GOVERNOR FOR FUEL INJECTION PUMP

Vernon D. Roosa, West Hartford, Conn.

Application December 8, 1955, Serial No. 551,944

5 Claims. (Cl. 123—140)

This invention relates to an improved governing means for an engine fuel pump. The present application is a continuation-in-part of my copending application Serial No. 457,903, filed September 23, 1954.

The improved governor means of the present invention is intended for use with an engine fuel injection pump of the type which is driven by the engine to which it supplies fuel and which pump is provided with a valve or other movable control member for varying the fuel flow to, and hence the speed of, the engine. One aim of the present invention is to provide an improved governor for use with fuel pumps which is capable of more effective speed regulation and which is arranged to be mounted in an improved manner with respect to the fuel pump.

A more specific aim of the present invention is to provide a governor which can be mounted directly on the rotor of the fuel pump and which is of simplified construction whereby it may be fabricated and assembled in an economical and convenient manner.

Another specific aim is to provide a governor which is responsive to both speed and the rate of change of speed in such manner that it will provide sensitive regulation to engine speed without being adversely affected by momentary surges or fluctuations in engine speed requiring no fuel regulation.

Other objects will be in part obvious, and in part pointed out more in detail hereinafter.

The invention accordingly consists in the features of construction, combination of elements and arrangement of parts which will be exemplified in the construction hereafter set forth and the scope of the application of which will be indicated in the appended claims.

In the drawings:

Fig. 1 is a side view of an exemplary fuel pump, a portion of the pump being in cross section to show the governor means of the present invention applied thereto;

Fig. 2 is an enlarged end view of the governor as mounted on the fuel pump rotor; and

Fig. 3 is a cross sectional view taken along the lines 3—3 of Fig. 2.

Referring to the drawings, the improved governor means of the present invention is shown installed in a fuel pump of the type shown in my prior Patent No. 2,641,238, granted June 9, 1953, to which reference may be had for a description of details of construction not covered by the present specification. The following description of the pump will be limited only to those portions of the pump which are involved in the present invention and as to which an explanation is deemed necessary for a complete understanding of the present invention.

As best shown in Fig. 1, the fuel pump includes a head 10 having a central cylindrical bore 11 in which is disposed a rotor 12. Integrally formed on the rotor 12 is an enlarged pump containing section 13. The right-hand section of the rotor 12 which is disposed in the central bore 11 and which may be referred to as the distributor, contains fluid passages (not shown) by means of which fuel is alternately fed to the pumping section and released from the pumping section through the outlets 14, which in turn are adapted to be connected by conduits or injection lines to injection nozzles in the engine cylinders. The amount of fuel admitted to the distributor and hence the output of the pump is regulated by a control valve (not shown) which receives fuel from a pick-up or

2

feed pump located in the outer end 15 of the head 10 and meters the fuel to the fluid passages of the rotor.

Secured to the head 10 is a housing 20 having an internal cavity 21 and formed with a mounting flange 22 by means of which the pump may be secured to a desired support such as the skirt of the engine with which the pump is associated. In accordance with the invention, the rotor 12 need not be provided with an elongated drive shaft extending outwardly of the flange 22 but is provided merely with a stub shaft 30 integrally formed thereon and having a slot or groove 28 at its outer end as shown in Fig. 2 by means of which the rotor may be attached to a driving shaft extending from or connected to the engine. By use of such a stub shaft the problem of attaining proper alignment of the pump is greatly reduced. In addition, it is unnecessary to provide any bearing surfaces for the shaft other than the rotor itself.

In accordance with the invention, a governor 29 of simplified and improved construction is disposed on the stub shaft 30. The stub shaft 30 is formed immediately adjacent the rotor 12 with a portion 31 of square cross section which serves as a means for mounting a drive plate 32 which has a center aperture complementary to the flange 31. The drive plate 32 is axially retained on the flange 31 by means of the snap ring 33 which is received in arcuate grooves (not shown) formed diagonally of the corners of the square shaft portion 31. An outer cage member 34 in the form of a thin-walled cylinder or tube is mounted coaxially and about the outer periphery of the drive plate 32 and is suitably fixed thereto, such as by brazing. An inner cage member or weight retainer 35 is received within the outer cage member 34 and axially retained therein by the spinning over of the end of the outer cage member as at 36. The inner cage member 35 is so dimensioned with respect to the outer cage member 34 that it may rotate relative thereto. Engaged between the inner end of the inner cage 35 and the drive plate 32 is a friction disc 37 fabricated of suitable material having a high coefficient of friction such as neoprene. The friction disc 37 provides a driving connection between drive plate 32 and the inner cage 35 which can slip if the rotative speed of the drive plate is suddenly increased or decreased.

As best shown in Figs. 2 and 3, the inner cage 35, which may be made of sheet metal, is formed with a plurality of rectangular pockets 38 in each of which is seated a governor weight 39 having a generally trapezoidal shape. The governor weights 39 are notched at 40 to provide inwardly extending fingers 41. A sleeve 42 which is axially slidably mounted on the stub shaft 30, has a flange 43 at its inner end in engagement with the fingers 41 of the governor weights 39. The governor weights are adapted to pivot on the apex or corner 44 thereof which engages the outer corner 45 of the pockets 38. The center of gravity of the weights 39 is at the left of the apex 40 as viewed in Fig. 3, with the result that as the cage 35 is rotated, the weights will tend to pivot outwardly responsive to centrifugal force about the apex 44, thus applying an axial force in a left-hand direction to the flange 43 of the sleeve 42 by the fingers 41 of the weights and a counter-acting force through the apexes 44 to the back plate 46 of the inner cage 35 which in turn abuts against the friction disc 37.

The sleeve 42 cooperates with a pivoted lever or governor arm 50. The end 51 of the lever has a bent-over portion 52 for engagement with a flange 53 on the left-hand end of the sleeve 42, the sleeve flange 53 being formed with ears 54 to abut the flanges 52 of the lever 50, thus preventing the sleeve from rotating. The lever 50 is pivoted at 55 about a pivot bar 56 which may be formed of square bar stock having two surfaces milled to form a fulcrum 57 about which the lever 50 is piv-

oted. The end of the lever 50 opposite from the governor is provided with a spring seat 58 in the form of a conical projection about which is mounted a governor return spring 60, the force of which may be regulated by turning the control lever 61. As will be understood, the lever 50 is adapted to be connected by suitable linkage (not shown) to the control valve previously mentioned in a manner whereby clockwise movement of the lever will result in a decrease in fuel flow and conversely, counterclockwise movement of the lever will result in an increase in fuel flow. The force of the governor return spring 60 is applied to the sleeve 42 through the lever 50. Sleeve 42 bears against the weights 39 which in turn are mounted on the cage 35 whose back plate 46 abuts against friction disc 37. Thus cage 35 is biased into engagement with disc 37 by the governor return spring 60.

It is believed that the operation of the governor means of the present invention will be apparent from the foregoing description taken together with the following explanation. As has been previously described, the governor weights are arranged to pivot about their apexes 44 responsive to rotation of the governor cage 35. In this manner the centrifugal force developed by the weights is directed axially of the rotor through the drive plate 32 in a rightward direction, as viewed in Figs. 1 and 3. Thus, the thrust of the governor is absorbed by the rotor 12 and it is unnecessary to provide additional bearings or other supports for the governor. If, during the operation of the pump and governor combination, a momentary surge or fluctuation in engine speed should occur, the friction disc 37 which has been provided in accordance with this invention as the driving connection between the inner cage member 35 and the drive plate 32 will permit the drive plate 32 to slip relative to the inner cage member 35, so that the surge in speed will not cause an overcorrection of the required fuel flow to the engine. The amount of pressure exerted on the friction disc 37 and hence the frictional force between drive plate 32 and cage member 35 will vary with engine speed since as the speed of rotation increases the thrust of the pivoted weights 39 against cage member 35 will increase. Thus, any tendency of the drive to slip at higher speeds is overcome while at lower speeds sufficient slippage is provided to smooth out any rough or uneven operation of the engine which is likely to occur at lower speeds.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim:

1. In a fuel pump governor, a drive shaft, a supporting member mounted on the shaft for rotational and axial movement relative thereto, a driving member fixed to the shaft on one side of the supporting member, an axially slidable control member on the other side of the supporting member, a plurality of weights pivotally mounted on the supporting member and engaging the control member to exert a thrust therebetween when subjected to centrifugal force due to rotation, and means forming a friction surface between the supporting member and driving member which is subjected to a compressive force responsive to the thrust on the supporting member.

2. In a fuel pump, a rotor for connection to a drive shaft, a governor driving member in the form of a plate

fixed to the rotor, a cage mounted for rotation relative to the rotor having a flat end surface adjacent the plate, a friction member between the end surface of the cage and the driving member, a control member mounted for movement axially of the rotor, and governor weights carried by the cage and pivotally mounted to exert a thrust between the control member and the cage when the cage is rotated, thus compressing the friction member between the end surface of the cage and the driving member.

3. In a fuel pump, a rotor, a drive member for the rotor, a drive plate abutting one end of the rotor and mounted for rotation therewith, a cage mounted for rotation relative to the rotor and movable axially on the drive member, said cage having an end plate facing the drive plate, a friction disc between the end plate and drive plate, a spring loaded control member movable axially on the drive member and disposed adjacent the cage on the side thereof opposite from the rotor, and a plurality of weights pivotally mounted on the cage for movement responsive to centrifugal force, said weights being operatively connected to the control member to exert a thrust on the control member in a direction away from the rotor and on the cage in a direction toward the rotor.

4. In a fuel pump, a body provided with a cylindrical cavity forming a hydraulic head, a rotor mounted for rotation in the cavity and supported against axial movement relative to the body, a stub shaft on the end of the rotor for connecting the rotor to driving means for imparting rotational movement to the rotor, and a governor mounted on the stub shaft comprising a cage rotatably supported on the stub shaft adjacent the rotor, yieldable connecting means between the cage and rotor, a spring loaded control member mounted for axial movement on the stub shaft on the side of the cage opposite from the rotor, and a plurality of weights mounted on the cage for movement responsive to centrifugal force when the cage is rotated, said weights being operatively connected to the control member to exert a thrust on the control member in a direction away from the rotor and to exert a thrust on the cage in a direction toward the rotor.

5. In a fuel pump, a body provided with a cylindrical cavity forming a hydraulic head, a rotor mounted for rotation in the cavity and supported against axial movement relative to the body, a stub shaft having a portion thereof of irregular cross section on the end of the rotor for connecting the rotor to driving means for imparting rotational movement to the rotor, and a governor mounted on said stub shaft comprising a cage having an open end and a closed end, said open end facing away from said rotor and the closed end having an opening of irregular cross section complementary to the irregularly cross sectioned portion of the stub shaft so that the cage will be supported on said irregularly cross sectioned portion of the stub shaft, a spring loaded control member mounted for axial movement on the stub shaft on the side of the cage opposite from the rotor, and a plurality of weights mounted within the cage for movement responsive to centrifugal force when the cage is rotated, said weights being operatively connected to the control member to exert a thrust on the control member in a direction away from the rotor and to exert a thrust on the cage in a direction toward the rotor which is supported and absorbed by said rotor.
